ALEXANDER LAUBSCHER, OF BRIDGEPORT, CONNECTICUT, ASSIGNOR TO
WHEELER & WILSON MANUFACTURING COMPANY, OF BRIDGEPORT,
CONNECTICUT, A CORPORATION OF CONNECTICUT.

SMOCKING ATTACHMENT FOR SEWING-MACHINES.

No. 797,207.

Specification of Letters Patent.

Patented Aug. 15, 1905.

Application filed January 3, 1905. Serial No. 239,459.

To all whom it may concern:

Be it known that I, ALEXANDER LAUBSCHER, a citizen of the United States, residing at Bridgeport, in the county of Fairfield and State of Connecticut, have invented a certain new and useful Improvement in Smocking Attachments for Sewing-Machines, of which the following is a full, clear, and exact description.

This invention relates to a smocking attachment for sewing-machines; and its object is to provide a device of simple construction and easy adjustment whereby the operator may quickly, easily, and accurately manipulate the material to form a honeycomb effect with uniformly-spaced rows of staggered tying-stitches.

The invention consists, fundamentally, of a fold-guide about which the cloth is bent and having a stop-slot for determining the spacing of consecutive tying-stitches. Preferably employed in connection with this fold-guide are a fold-guard to keep the fold of material clear of the needle and a guide-plate, which also supports the guard-plate.

In the accompanying drawings, illustrating the invention, in the several figures of which like parts are similarly designated, Figure 1 is an elevation of the front side of a Wheeler & Wilson D12 zigzag-sewing machine, the fold-guide-supporting arm being broken in two. Fig. 2 is a plan view of my device, the fold-guide-supporting arm being broken in two, the view also showing the throat-plate, front and back slide-plates, and a portion of the bed-plate of the sewing-machine. Fig. 3 is a plan view of the fold-guide detached. Fig. 4 is a plan view of the guide-plate and fold-guard detached. Fig. 5 is a perspective view illustrating the folding, gaging, and guiding of the material. Fig. 6 is a right or top side view of the finished product. Fig. 7 is an under side view of a portion of the finished product.

The invention may be and preferably is used in connection with a zigzag-sewing machine having an automatic stop-motion such as that herein indicated in the present drawings and more particularly described in Patent No. 680,665, granted to the Wheeler & Wilson Manufacturing Company, assignee of Donald Noble, and dated August 13, 1901, for "Stopping mechanism for sewing-ma-

chines." Further, the mounting of the fold-guide and the means employed for its adjustment and manipulation are substantially the same as are illustrated and described in Patent No. 689,100, granted to the Wheeler & Wilson Manufacturing Company, assignee of Alexander Laubscher, and dated December 17, 1901, for "Tuck-folder for sewing-machines."

1 designates the bed-plate of the sewing-machine; 2, the overhanging arm; 3, the band-wheel; 4, the stop-motion mechanism; 5, the needle; 6, the needle-bar; 7, the take-up; 8, the needle-thread tension; 9, the face-plate; 10, the needle-bar connection; 11, the back slide-plate; 12, the front slide-plate; 13, the throat-plate, and 14 the segment-lever for vibrating the needle-bar gate 15 so as to obtain the zigzag-stitch, and all of these parts and the operating mechanism for such of them as move may be and are here shown as they are used in the Wheeler & Wilson D12 zigzag-sewing machine.

The invention has to do with the parts immediately used for folding, guiding, and gaging the material and spacing the tying-stitches.

16 is a guide-plate adjustably secured to the back slide-plate 11 by screws 17, passing through a slot or slots 18, with a washer 19 under the heads of the screws.

20 is a fold-guard having a longitudinal slot or slots 21 and screws 22, whereby it is adjustably secured to the guide-plate 16.

23 is a fold-guide having a slot 24 and screws 25, whereby it is adjustably secured to an arm 26, a washer 27 being interposed under the heads of screws 25.

The leading end of the fold-guide 23 is made as an elongated blade 28, and in the heel of the blade is a needle-hole 29, out of which leads a slot 30, and this slot has cut in it laterally or at right angles an outlet-slit 31, which is backed by the wall 32, and this wall 32 serves as a stop against which the previously-made tying-strokes abut while forming the next subsequent stitch. From needle-hole 29 to stop-wall 32 is substantially the length of the distance between the tying-strokes, and because the parts 29 to 32 subserve the purpose of fixing the maximum limit of distance between tying-strokes I have herein referred to them collectively as a "stop-slot."

The guide-plate 16 is made with a downwardly-bent leading end 33, (see Fig. 5,) which is extended as a complementary blade 34, and said guide-plate has in its leading end a needle-notch 35 to register with the needle-hole 29 in the fold-guide. The fold-guard 20 is arranged next the notch 35 and beyond it toward the operator, and its free end 36 is bent upwardly and then curved downwardly and its extreme edge rests upon the downwardly-bent leading end of the said guide-plate 16. In use the edge of the guide-plate 16 overlaps the edge of the fold-guide, as indicated in Figs. 1 and 2, and the needle-holes 29 and 35 aline when the parts are in operative position.

The fold-guide 23 for the purposes of this invention must have an adjustment vertically with relation to the throat-plate and also must be capable of being moved horizontally toward and from the operator, and in order to obtain these movements the arm 26, which supports the said fold-guide, may be mounted substantially as in Patent No. 689,100, above referred to, and as herein shown the stand for the arm comprises a base 37, screwed down to any suitable support, such as the machine-table or bench, and on this stand is mounted the turn-table 38, having uprights 39 applied to it, which serve as bearings for the shaft or pintle 40, connected with the arm 26 in such way that the arm may be adjusted vertically. The turn-table 38 permits of the horizontal adjustment of the arm. In order to retain the arm 26 in its vertical adjustment, a set-screw 41 is employed, and to impart a constant downward pressure to the arm a compression-lever 42 is mounted on the turn-table and is held in forcible contact with the arm by means of a spring 43 and a spring tension-screw 44. In order to position the arm and the fold-guide, a stop 45 rises from the base 37 and a set-screw 46 is placed in a lug 47, projecting from the turn-table 38, so as to contact with the said stop, and thus limit the motion of the turn-table in one direction.

The operation is as follows: Referring to Figs. 5, 6, and 7, the material 48 is folded over the blade 28 of the fold-guide 23 with the right side of the material down, so as to bring the leading end of the material at a point to place the first fold at the desired distance from its edge. The first tying-stitches 49 are then placed distant from the edge of the material, either the distance represented by the length of the slot 30 back of the needle or half that distance, and after the formation of the first knot of tying-stitches the material is adjusted in the direction of the arrow *b*, Fig. 5, until the tying-stitches register against the wall 32 of the stop-slot. The second set or knot of tying-stitches being completed, the first knot of stitches is passed out through the slit 31 and the second knot of tying-stitches adjusted against said wall, and these

operations are continued for each successive knot of tying-strokes. The first fold being completed, the material is moved in the direction indicated by the arrow *a*, Fig. 5, and positioned so that the fold-guard 20 will hold the fold away from the needle and the base of the fold may be guided along the edge of the leading end 33 of the guide-plate. For convenience in gaging the first of the tying-strokes of the new fold so that they will be staggered with relation to the tying-strokes placed in the previous fold the fold-guard may be, as shown in the drawings, of a width substantially half the length of the slot 30 back of the needle-hole, so that in starting the rows of tying-strokes it is only necessary to register the first stitch of the shorter row 50 to the edge of the fold-guard next the operator when starting the longer row of tying-strokes and to register the second knot of tying-strokes of the longer row, containing the stitches 49, in like manner to start the shorter row of tying-strokes; but this gaging affects only the first knot of tying-strokes, since the succeeding tying-strokes comprised in the row are gaged, as previously explained, by registering the tying-strokes against the wall 32 of the stop-slot.

While the fold-guard is important as a convenient means for feeding the material to the action of the needle, it is possible to dispense with it, and in that case the operator must manually hold the previously-made fold out of line with the movement of the needle.

As already indicated, the fold-guide is adjustable vertically for different thicknesses of material and is movable laterally in a horizontal direction for inserting and removing the goods. As also sufficiently indicated, the fold-guide and the guide-plate are adjustable to space the rows of tying-strokes at different distances apart in the direction of the length of the feed of the material.

What I claim is—

1. In a smocking attachment for sewing-machines, a fold-guide, and a co-operative complementary member, said fold-guide provided with a stop-slot, having a lateral slit at one end and a wall located at the far side of this slotted or open end adapted to space the tying-strokes equidistantly.

2. In a smocking attachment for sewing-machines, a fold-guide and a guide-plate, said fold-guide provided with a stop-slot open at one end and having a needle-hole at its other end, the wall of the open end of the stop-slot located a distance from the needle-hole equal to the distance required for the proper spacing of the tying-strokes.

3. In a smocking attachment for sewing-machines, a fold-guard, a fold-guide, and a guide-plate, said fold-guide provided with a stop-slot open at one end and having a needle-hole at its other end, the wall of the open end of the stop-slot located a distance from the

needle-hole equal to the distance required for the proper spacing of the tying-stitches.

4. In a smocking attachment for sewing-machines, a fold-guard, a fold-guide, and a guide-plate, said fold-guard, fold-guide, and guide-plate adjustably secured relatively to the line of tying-strokes, and the fold-guide provided with a stop-slot at one end and having a needle-hole at its other end, the wall of the open end of the stop-slot located a distance

from the needle-hole equal to the distance required for the proper spacing of the tying-strokes.

In testimony whereof I have hereunto set my hand this 31st day of December, A. D. 1904.

ALEXANDER LAUBSCHER.
